FRED NEALE, OF CLEVELAND, OHIO, ASSIGNOR, BY MESNE ASSIGNMENTS, TO THE
MIDLAND STEEL PRODUCTS COMPANY, OF CLEVELAND, OHIO

COMPRESSOR CONTROL APPARATUS

Application filed March 28, 1927. Serial No. 179,066.

The invention relates to compressed air systems, and more particularly to the governor or control of a continuously running compressor.

5 The general object of the invention is to provide a control mechanism for a continuously running compressor wherein the inlet or relief valve is held open when the reservoir pressure reaches the desired maximum 10 pressure and is permitted to function normally when the pressure in the system drops to a predetermined minimum. The present invention is characterized by the fact that a pair of latches cooperate to hold the inlet 15 or relief valve open, and that one of these latches is moved to actuate the other latch by means responsive to pressure changes in the system.

20 The invention further consists in the several features hereinafter set forth and more particularly defined by claims at the conclusion hereof.

25 In the drawings Fig. 1 is a detail vertical sectional view of a governor embodying the invention;

Fig. 2 is a detail sectional view taken on the line 2—2 of Fig. 1;

Fig. 3 is a detail view showing the position of the latches under maximum pressure 30 conditions;

Fig. 4 is a detail view showing the position of the latches under minimum pressure conditions;

Fig. 5 is a detail sectional view generally 35 similar to Fig. 1, showing a modification of one of the latches;

Fig. 6 is an elevation view of a control 40 governor for a multicylinder compressor, the top cover being removed;

Fig. 7 is a detail sectional view taken on the line 7—7 of Fig. 6;

Fig. 8 is a side elevation view of the control shown in Fig. 6;

Fig. 9 is a detail sectional view of a governor embodying the invention showing certain modifications of the latches.

45 In Fig. 1 I have shown a portion of the compressor cylinder 6 with the piston 7 working therein and the head 8 provided with an inlet port 9 communicating with atmosphere 50

and controlled by the usual type of automatic inlet valve 10 guided in a bushing 11 and normally urged to its seat by a spring 12 interposed between said bushing and a washer 13 locked to the exposed upper end of the 55 stem.

A pair of latches 14 and 15 are associated together to control the action of the valve 10, the latch 14 engaging the valve 10 to hold it in open position so that the compressor runs 60 idle, that is, the air drawn in through the port 9 upon the suction stroke is pushed out again through said port to atmosphere.

The latch 14 is pivotally mounted on a pin 65 16 carried by spaced arms 17, similar to arms 55 hereinafter described, between which the latch moves, said arms projecting from a base plate 18 secured to the cylinder head of the compressor adjacent the inlet valve and having an opening 19 through which the upper end of the valve and its spring projects. An opening 20 is provided in the free end of this latch through which a pin 21, mounted in the uprights or arms 17, passes, the diameter of the opening 20 being several times larger than that of the pin whereby the latch is allowed to swing upwardly or downwardly 70 through a predetermined angle but is limited in its movement by said pin 21.

75 The latch 15 has a tubular portion 22 slidably mounted in the bore of an actuator or lever 23 which has a slotted end 24 receiving an upright 25 between its bifurcations and to which it is pivotally connected by a pin 26, 80 said actuator being moved by means responsive to pressure changes in the system, and a spring 27 is interposed between the end of the bore in said lever 23 and the end of a bore 28 in the tubular portion 22 and acts to force 85 said latch 15 outwardly into engagement with the latch 14.

The latch 14 has inclined surfaces 29 and 30 and the latch 15 may have similar surfaces 31 and 32 or may have its contacting end formed as a roller 33 mounted on a pin 34 carried by the slotted end of the tubular shank 22, as shown in Fig. 5. In either instance it will be noted that when the latch 15 is swung downwardly from its mid position it will engage the lower inclined surface 29 100

of the latch 14 and due to its wedging action will slide or roll thereon and lift the latch 14 upwardly to its limit, as shown in Fig. 4, under which conditions the inlet valve is free 5 to function normally so that the compressor acts to draw in air during the suction stroke, compress it during the compression stroke and force it past the discharge valve (not shown) to the reservoir. This action takes place under 10 conditions of minimum reservoir pressure. In either instance when the latch 15 is swung upwardly from its mid position it will engage the upper inclined surface 30 of the latch 14 and due to its wedging action, under the influence of the spring 27 which is 15 stronger than the inlet valve spring 12, it will slide or roll thereon and press down on the latch 14 which then engages the inlet valve stem and acts thereon to hold the inlet valve 20 in open position against the normal closing action of said valve so that the compressor runs idle. This action takes place under conditions of maximum reservoir pressure. The latch 15 and its actuator 23 are limited in 25 their swinging movement by ledges 23' on the base 18 forming a stop engageable with the bottom portion 24' of the part 24 so as to limit the upward swing of this latch.

In each instance the lever 23 is connected 30 beyond its pivot by a pin 35 to the flat-sided head 36 of a rod 37, said head slidably engaging the flat sides of the slotted end 24 so as to be maintained in proper alignment therewith. This rod carries a washer 38 and a nut 39 adjustably mounted on the lower threaded end thereof and the governor or controlling spring 40 is interposed between the base plate 18 and the washer and normally acts to swing the lever 23 and hence the latch 15 downwardly. The action of the spring 40 is opposed by the pressure of the fluid in the system and for this purpose a casing member 41 secured to the plate 18 by screws 41' is provided with an end plate 42 which with a movable cup or piston 43 with which the lower end of the rod 37 engages and a multiple bellows diaphragm 44 connected on one end to said plate 42 and at its other end to said cup 43 forms a pressure chamber 45 in communication with the reservoir or tank (not shown) through a port connected by a pipe 46 with said reservoir.

Thus, when the pressure in the reservoir reaches maximum value the piston 43 and 55 rod 37 are moved upwardly against the action of the spring 40 and this swings the latch-carrying end of the lever 23 upwardly, with the result heretofore pointed out of moving the latch 14 downwardly to hold the inlet valve 10 open so as to prevent the compressor from functioning, and when the pressure in the reservoir reaches a minimum value the spring 40 predominates and the piston 43 and rod 37 move downwardly and 60 this swings the latch-carrying end of the le-

ver 23 downwardly, with the result heretofore described of moving the latch 14 upwardly so as to allow the normal functioning of the compressor.

The sliding connection between the latch 15 and the lever 23 provides a lost motion connection which permits movement of the latches past their dead center position.

A cover 47, secured to the base by screws 48 passing through apertured ears 49 on said cover, fits closely over the ends of the pins 16 and 26 so that no special fastening means are required to hold said pins in place, this arrangement being shown in Fig. 2 in connection with the pin 26.

In the construction shown in Figs. 6 to 8, inclusive, the governor base 50 is secured by bolts 51 to the head 52 of a multicylinder compressor having automatically-opening spring-closed poppet inlet valves 53, each controlling the passage of air to its cylinder 54. The spaced upright arms 55 of the base 50 have a pivot pin 56 and a stop pin 57 mounted therein. A latch 58 is pivotally mounted on the pin 56 and has an enlarged opening 59 through which the stop pin 57 passes to limit the swinging movement of said latch similar to the latch 14. This latch 58 has a bar or yoke 60 welded or otherwise suitably secured thereto whose ends extend over and are adapted to engage the stems of the inlet valves 53. A latch 61 has a conical end 62 designed to engage the latch 58 and its tubular portion is slidably mounted in a bore in the lever 63 and pressed outwardly by a spring, as in the first-described construction.

The lever 63 is mounted similar to the lever 23 on a pin 64 carried by an upright 65 and is operatively connected intermediate its ends by a pin 66 to the rod 37 which is shown in detail in Fig. 1 associated with the pressure chamber 45. The extent of upward movement of the lever 63, and hence the latch 61, is limited by ledges 67 on the base 50 forming stops engaged by the bottom portions 68 of the lever 63, and a cover 70 fits over the operating mechanism and is suitably secured to said base.

This construction operates like the first-described construction to cause the latch 61 to 115 operate the latch 58 but in this instance said latch 58 operates to hold both inlet valves open under conditions of maximum reservoir pressure through the contact of the bar 60 with said valves or to permit both valves to function normally when said latch 58 is raised under conditions of minimum pressure.

In the construction shown in Fig. 9 the base 71 is secured to the cylinder head 8 and has an upright 72 projecting therefrom, said upright being bifurcated and one of said bifurcations being shown. The inlet-valve-engaging latch 74 is pivotally mounted between the bifurcations of the upright 72 on a pin 73 and is limited in its upward movement by 120 125 130

having a stop portion 75 engageable with a stop surface 76 formed at the base of the forked portions of this upright. The cooperative latch 77 is of tubular form, having a conically rounded outer end 78 engageable with the inclined surface 79 and 80 of the latch member 74, said latch being slidably mounted in the bore of an operating member 81 and normally urged outwardly by a spring 82 mounted in said bore and a bore 83 in said latch. The member 81 is formed as a casting and its rear portion is milled out on opposite sides to provide a flat faced part 84 which fits between the forked parts of the upright 73 to which it is pivotally connected by a pin 85 and which also receives the upper forked end 86 of a rod 37' otherwise similar to the rod 37 and similarly associated with the parts 38 to 45, inclusive, which have been described in connection with Fig. 1.

In this instance a laterally disposed lug 87 on the member 81 carries a stop pin 88 which works in an enlarged opening 89 in a stop lug 90 projecting from the base 71 and disposed in front of the lug 87, said pin 88 and lug 90 cooperating to limit the swinging movement of the operating member 81 and latch 77.

This construction operates like the first-described construction and causes the latch 77 to operate the latch 74 to hold the inlet valve open under conditions of maximum reservoir pressure or permit said valve to function normally when said latch 74 is raised under conditions of minimum pressure.

I desire it to be understood that this invention is not to be limited to any specific form or arrangement of parts except in so far as such limitations are specified in the claims.

What I claim as my invention is:

1. In a compressor control, the combination with the compressor and the pressure system supplied thereby, said compressor having an inlet valve controlling passage to atmosphere, of a pair of pivoted latches having inclined contacting surfaces and a lost motion connection relative to each other, spring means for holding said latches in engagement with each other under the action of said lost motion connection, one of said latches being operatively connected with the inlet valve of the compressor and moved by the other latch to hold said inlet valve in open position under maximum pressure conditions in said system, and means responsive to pressure changes in the system supplied by the compressor for moving the other latch to effect the movement of the first-named latch.

2. In a compressor control, the combination of a pair of engaging, swinging latches having contacting surfaces and a lost motion connection relative to each other, spring means for holding said latches in engagement with each other under the action of said lost motion connection, one of said latches being op-

eratively connected with the inlet valve of the compressor and moved by the other latch to hold said inlet valve in open position under maximum pressure conditions, means associated with each latch for limiting its swinging movement, and means responsive to pressure changes in the system supplied by the compressor for moving the other latch to effect the movement of the first named latch.

3. In a compressor control, the combination with a base mountable upon the compressor, of a latch pivotally mounted on said base and operatively connected with the inlet valve of the compressor to hold the same in open position under maximum pressure conditions, a latch, including a lever, pivotally mounted at one end on said base and a member slidably mounted on said lever and engageable with said first-named latch, said latches having inclined contacting surfaces, spring means for holding said last-named member in engagement with said first-named latch, means for limiting the pivotal movement of said latches, and means connected to said lever and responsive to pressure changes in the system supplied by the compressor for moving the said member to effect the movement of said first-named latch.

In testimony whereof, I affix my signature.

FRED NEALE.
